ELECTROACOUSTIC TRANSDUCER FOR
ACTUATING LOUD SPEAKERS

Milton Morse, New York, N. Y., assignor to University Loudspeakers Inc., New York, N. Y., a corporation of New York

Application May 7, 1946, Serial No. 667,964

3 Claims. (Cl. 179—126)

1

My present invention relates generally to the transmission of sound, and has particular reference to electro-mechanical transducers.

It is a general object of the invention to provide a carbon-grain transducer of improved design and enhanced conversion ability, i. e., ability to transform mechanically applied energy into faithfully responsive electrical energy.

The broader phases of my invention are applicable to various purposes, depending upon the source and nature of the applied energy. For example, the energy applied may be derived from a grooved record, as in the case of a phonograph pick-up, or it may consist of acoustic energy in the form of sound waves transmitted through the air, as in the case of a microphone. Because of its particular value and importance in the field of microphones, I have chosen herein to describe and illustrate the nature and advantages of the invention in the embodiment of a microphone and a microphone-loud speaker circuit.

As is well known, a carbon-grain microphone consists essentially of a pair of electrodes and a mass of carbon grains (or equivalent material) interposed between them, one of the electrodes (commonly referred to as a diaphragm) being mounted for vibration in response to sound-wave impulses impressed thereon. When inserted in series in a direct-current circuit, the vibrations of the diaphragm effect corresponding variations in the carbonaceous resistance path between the electrodes, and the current flowing in the circuit is thus caused to fluctuate in response to the sound-wave impulses.

In conventional microphones, the design is of such character that the average resistance is of relatively high order, usually eighty ohms or more, and the current transmitted is correspondingly minute. Such a current is adequate for the purpose of actuating an earphone, such as a telephone receiver, but requires considerable amplification in order to operate a conventional loud speaker. Accordingly, in public-address systems and the like, the necessary equipment has always heretofore included not only the microphone and the loud speaker, but also a relatively expensive and cumbersome amplifying apparatus as well.

In accordance with my invention, I am enabled to provide a microphone having an average resistance of such low magnitude that it is capable of transmitting a low-voltage current which is adequate, without amplification, to actuate a loud speaker of comparably low resistance. By

2

"low voltage" I intend to signify a voltage of the order of six volts, such as might be conveniently furnished by one or a few small dry-cell batteries or by an automobile storage battery, or the like. By "low resistance" I mean a resistance within the range of one to fifteen ohms, such as is manifested by the conventional loud speaker of a radio receiving set or a so-called public-address system.

10 So far as I am aware, no microphone of conventional or practical size or character has ever been made in which the average resistance is lower than about eighty ohms, and which has sufficient electro-acoustic conversion ability to adequately operate a loud speaker for public address purposes without amplification. This is due in part to the fact that a lower resistance would be unnecessary and undesirable in telephone circuits or the like, where a correspondingly high line resistance exists, and also to the electrical and mechanical difficulties which are encountered and which have not heretofore been successfully overcome.

25 The achievement of the present improved results is predicated upon a study of the factors influencing microphone resistance, current transmitting capability, and conversion ability, and upon the discovery that certain hitherto unknown or unrecognized critical relationships exist where relatively low average resistances are involved.

30 It is known that the impedance of a carbon-grain microphone is a function of the average grain size, of the operative electrode area, and of the spacing between electrodes. Thus, generally speaking, an increase in grain size will lower the resistance, whereas a decrease in grain size will raise it. In the conventional microphone the grains employed are usually of a size considerably smaller than 50-mesh (one fiftieth of an inch) and are most commonly of the order of 100-mesh to 200-mesh. Similarly, it may be stated as a general proposition that an increase in the spacing between the electrodes will increase the resistance, whereas a reduction in the spacing will decrease it; and in a smaller measure, an increase in operative electrode area (exposing the grains to a larger contact area) will decrease the resistance, while a reduction of such area will increase it.

35 With the object in view of having the microphone transmit, at low voltage, a current of sufficient magnitude to actuate a loud speaker without any preliminary amplification, it becomes important to establish a matched imped-

ance between the microphone and the loud speaker, and the problem resolves itself to the design of a microphone having a resistance of less than fifteen ohms, which is the resistance most commonly manifested by the average loud speaker.

In achieving this object, reliance cannot be placed solely on an enlargement of the operative electrode surface without entailing mechanical and other difficulties incident to impractically large dimensions. Recourse is therefore preferably had to an enlargement of the ratio between the grain size and the spacing between electrodes. To avoid the practical difficulties involved in providing for and maintaining too minute dimensional relationships between the electrodes, this involves an enlargement of the grain size.

My experiments have shown that as the ratio between grain size and electrode spacing increases toward unity, there is a critical relationship between grain size and electrode spacing which must be maintained in order to avoid such impairment of conversion ability as to defeat the desired objective. Moreover, at the critical ratio, the conversion ability has been found to be of surprisingly good efficiency, considerably greater than any conversion ability heretofore present in conventional microphones.

It is therefore a feature of my invention to provide a carbon-grain microphone in which the operative electrode area, the average grain diameter, and the spacing between electrodes, are so chosen that there may be achieved not only the desired low average resistance but also a conversion ability of high order. This result is capable of accomplishment, in accordance with my invention, by a special design in which the spacing between the electrodes is caused to be no less than 2.0 and no more than 2.6 times the average grain diameter. Thus, where the grain size is in the preferred range of 50-mesh to 10-mesh (one tenth of an inch), the spacing between the electrodes is caused to lie between the dimensional values of 0.04 and 0.26 inch. A thoroughly practical construction lying within this range, and involving an over-all microphone size of conventional character, employs grains of substantially uniform size whose average diameter is 0.05 inch (20-mesh), and has the electrodes mounted between 0.10 and 0.13 inch apart.

It is also important that the vibrations of the diaphragm be unimpeded by grain-retaining washers or similar structure, and, to the contrary, that the vibratable electrode be as free as possible to move in response to the sound-wave impulses impressed upon it. This I achieve by a special construction and assembly of parts, involving the employment of complementary electrodes which are of generally concave and convex configuration, the convex electrode having a base which defines a cylindrical contour. By encircling this base with a collar which is separated from the base by a clearance gap, the convex electrode is left entirely free to vibrate in the direction of the cylinder axis, and at the same time the clearance gap may be made small enough, relative to the grain size, to prevent escape of the grains through it.

A further feature of the invention resides in the provision of a novel unitary structure which not only supports the microphone in an efficient, preferably pivotable, relation to a handle, but serves also as a convenient means for accommodating one or more low-voltage dry-cell batteries with which the microphone is to be connected in series.

The preferred way of achieving these general objects and advantages, and such other objects and advantages as may hereinafter appear or be pointed out, is illustratively exemplified in the accompanying drawings, in which:

Figure 1 is a diagrammatic representation of an illustrative sound-transmitting circuit to which the invention may be applied;

Figure 2 is a longitudinal cross-sectional view through a microphone of the present improved design, shown as part of a unit including a battery-accommodating handle;

Figure 3 is a cross-sectional view taken substantially along the line 3—3 of Figure 2, including the rear or free end of the handle;

Figure 4 is an enlarged fragmentary cross-section taken substantially along the line 4—4 of Figure 2;

Figure 5 is a perspective view of the entire microphone-handle assembly, showing its relation to a connecting cord of conventional type; and

Figure 6 is a graph depicting certain relationships observed by experimentation.

One of the desirable objectives achieved by the present invention is depicted in Figure 1, in which I have diagrammatically represented a microphone 10 connected in series with a conventional loud speaker 11, and with a source of low voltage direct current 12. It will be observed that this circuit is devoid of the conventional amplifier which has been regularly employed as a necessary accessory in the circuit between a microphone and a loud speaker.

The microphone 10 and the battery 12 may be conveniently assembled in the form of a unitary structure, as shown in Figure 5. In a manner presently to be described in greater detail, the microphone 10 is secured to one end of a cylindrical handle 13 adapted to accommodate one or more simple dry cell batteries. At the rear or free end of the handle 13, recesses are provided for the purpose of removably receiving a conventional two-pronged connector 14 electrically secured to the end of a flexible cord 15. By connecting one end of the cord 15 to any conventional loud speaker, and the other end to the handle 13, a sound-transmitting equipment is available, consisting in its entirety of the elements mentioned, and requiring no cumbersome or expensive amplifying apparatus. The advantages of this simplified arrangement will be apparent to those conversant with the art of ordinary so-called public-address system.

The microphone of the present invention is shown most clearly in Figure 2. A metal housing is provided, preferably of substantially cylindrical shape, and consisting (in the illustrated embodiment) of a forward element 16 and a rear element 17, the latter being fitted snugly over a reduced rearwardly-directed skirt on the element 16. The elements 16 and 17 may be composed, for example, of aluminum or the like, and may be die-cast, stamped and drawn, or formed in any other convenient manner.

Snugly fitted within the portion 16 is a supporting element 18, which may be also composed of aluminum or the like, and which is formed with a forwardly-projecting skirt 19 and a rear portion having a cylindrical bore 20 formed therein. Between the skirt 19 and a spacing ring 21 is clamped the marginal portion of a diaphragm 22. Between the spacer 21 and a similar spacing ring 23 is clamped the marginal portion of an inner front wall 24. This wall, and the outer front wall 25 (formed, preferably, as an integral part of

the housing element 16, constitute the front of the microphone toward which the sound wave impulses are directed in conventional fashion. Preferably, each of these walls is provided with a series of openings 26 to permit the passage of the sound waves. The walls 24 and 25 are commonly referred to as acoustic filters. Both walls are preferably composed of aluminum or the like, and the spacers 21 and 23 may be composed of similar material.

Clamped in position behind the inner acoustic filter 24, I provide a flexible moisture-proof barrier 27, which may be composed, for example, of rubber, rubberized silk, Vinylite film, or the like, approximately two-thousandths of an inch thick. As will be well-known to those skilled in the art, this wall is of limp and unstretched character and serves merely to prevent the passage of undesirable moisture to and through the diaphragm 22.

The diaphragm 22 is of more or less conventional character, being composed of aluminum, aluminum alloy, or the like, and being approximately two-thousandths of an inch thick. It has a slightly bowed shape, as shown, except that its marginal portion lies flat in a single plane in clamped engagement between the parts 19 and 21. Adjacent to this margin, the diaphragm 22 may be provided with the well-known diagonal flutings 28 (not shown in detail) which enhance the freedom of vibration of the central bowed portion under the impact of the sound waves which pass through the filters 25 and 24, and through the moisture-proof diaphragm 27. The diaphragm 22 may be provided, if desired, with one or more minute holes 29 to prevent any entrapped air to dampen or impede the desired free vibration of the diaphragm.

As is well known, it is the central portion of the diaphragm which serves as the operative electrode. I prefer to employ a convex electrode 30 of substantially hemispherical shape, this element being composed of brass or copper, plated with gold or platinum. This element is approximately two-thousandths of an inch thick and is mounted in association with the diaphragm by initially providing the latter with a central opening and by forming flanged fingers on the rear margin of the element 30, for clamping engagement with the margins of the hole in the diaphragm. These fingers have not been shown in the present drawings, in which, for the sake of convenience and simplicity, the convex electrode 30 has been shown as an integral part of the diaphragm 22 as a whole.

For a purpose presently to be described, the base of the electrode 30, i. e., the portion adjacent to its point of connection with the diaphragm 22, is purposely caused to have a cylindrical contour. This cylindrical shape is best observed in Figure 4.

The vibratable electrode 30 cooperates with a complementary concave electrode which I have shown in the form of a cup-shaped plug 31 mounted within the bore 28 of the part 18, and insulated from the latter by means of a cylindrical sleeve or bushing 32 of insulating material, such as Bakelite or the like. The part 31 is composed of copper or brass, and its concave face is plated with gold or platinum.

In the space between the concave face of the electrode 31 and the convex outer face of the electrode 30, a mass of carbon grains 33 are arranged. They may be inserted and withdrawn from this space through a central opening in the element 31, which is plugged by a threaded element 34. The latter is accurately constructed and machined so

that when it is in position, as shown, its inner face is concave and constitutes a continuing portion of the concave operative face of the electrode 31. With this objective in view, the plug 34 is preferably composed of copper or brass, and its inner concave end is plated with gold or platinum.

The carbon grains 33 are kept within the space between the electrodes by a retainer lip or collar 36 which encircles the cylindrical base of the electrode 30 and projects part-way across the annular inner end of the space within which the carbon grains are accommodated. This relationship of parts is shown most clearly in Figure 4, and it will be observed that there is a clearance gap 37 between the collar 36 and the cylindrical base of the electrode 30. This gap permits free vibration of the electrode 30 in the direction of the cylinder axis, yet it may be made small enough, relative to the average size of the carbon grains employed, to prevent escape of the latter through it. For example, where the carbon grains have an average diameter of 0.05 inch, the clearance gap 37 may be approximately 0.01 inch, even slightly larger than this.

The unique capabilities of the present microphone and microphone circuit are predicated upon the relationships which experimentation has shown to exist and which are depicted in the graph of Figure 6.

If the vertical axis of this graph is caused to represent the conversion ability of the microphone, while the horizontal axis represents the spacing between the electrodes 30 and 31, in terms of the average grain diameter, it will be understood, at the outset, that the ratio between grain diameter and spacing cannot be less than unity. Under these circumstances, there would be a single layer of carbon grains between the two electrodes, and vibration of the electrode 30 would be entirely precluded, except such minute movement as may be permitted by the compressibility of the carbon grains. Conversion ability under these circumstances is practically nil, as indicated by the portion 38 of the graph. As the spacing between the electrodes is increased, the conversion ability is found to rise suddenly and markedly as the spacing reaches a magnitude twice as great as the average grain diameter. Surprisingly enough, however, a slight increase of the spacing beyond a value approximately 2.3 times the average grain diameter causes an almost equally sudden falling off of conversion ability, as represented by the portion 39 of the graph. At a spacing almost equal to three times the average grain diameter, the conversion ability rises slightly, as indicated at 40, and as the spacing is gradually increased beyond this amount, the conversion ability diminishes rather gradually, as indicated by the portion 41 of the graph.

It is my theory that the behavior of the microphone so far as electro-mechanical conversion ability is concerned, is explained as follows: When the space between the electrodes is less than two times the average grain diameter, the carbon grains tend to bind or "freeze," thereby seriously impeding, if not entirely preventing, free vibration of the vibratable electrode or diaphragm. At or slightly beyond an electrode spacing which is twice the average grain diameter, an optimum relationship of parts manifests itself, wherein an effective current path exists having a resistance of minimum magnitude but of maximum variability. This path extends through a maximum of two grains, one of which establishes a low-resistance contact with one of the gold-

plated or platinum-plated electrodes, the other of which establishes a similar low-resistance contact with the other gold-plated or platinum-plated electrode. The points of contact resistance are thus only three in number, two at the electrodes, the third between the two carbon grains. In the range of spacing depicted by the portion 39 of the graph, however, the ratio between electrode spacing and grain size becomes sufficiently large for grain slippage and added inter-grain contacts to cause a loss in electro-mechanical conversion ability. Thereafter, as the spacing increases, the physical weight of the mass of carbon grains begins to manifest itself by a "loading" of the vibratable electrode, and the sensitivity of the microphone is thereby impaired. Moreover, as the space between the electrodes increases, the resistance of the carbonaceous current path increases, and this also lowers efficiency and impairs conversion ability.

Another reason for the extremely high conversion ability in the peaked portion of the graph of Figure 6 lies in the arrangement of the carbon grains. In the range in which the electrode spacing is between 2.0 and 2.6 times the average grain diameter, and especially in the range between 2.1 and 2.3, the grains group themselves in such a way as to form an assembly which is stable (not readily rearranged) and which nevertheless does not pack or "freeze." This type of grouping results in maximum translation of the energy imparted to the moving electrode into effective variations in pressure between carbon grains, these pressure variations being (as is well known) the basic cause of conversion ability.

By way of comparison, when the movable electrode of an ordinary microphone receives an impulse of movement, it causes a new arrangement of carbon grains by the sliding of one grain over another, and it also causes additional compression between the grains. It is only the compression which results in effective conversion ability; the sliding of the grains over one another causes only undesired noise and no electro-acoustic conversion. In the conventional type of carbon microphone, the greater portion of the energy applied to the moving electrode is wasted in this fashion. In the present microphone, on the other hand, this waste of energy, due to sliding of the carbon grains, is minimized if not entirely eliminated. In the peaked portion of the graph of Figure 6, especially at its upper end, the carbon grains arrange themselves in such a manner that any pressure on the moving electrode serves mainly to cause effective variation in compression between the grains. This is due to the fact that the size relationship makes it impossible for any substantial amount of inter-grain slippage to occur.

It is also a feature of my invention that in the range represented by the peaked portion of the graph, there is no jamming or "freezing" of the carbon grains into a rigid mass. It is thus unnecessary to employ any special springs or compressible electrodes to avoid such a result.

In conventional microphones, the conversion ability lies along the portion 41 of the curve depicted in Figure 6, since the ratio of grain size to electrode spacing is well below one to three, i. e., the spacing in terms of average grain diameter is well over three.

The behavior of the carbon grains, and of the resultant conversion ability of the microphone, in the range where the ratio between grain diameter and electrode spacing increases toward unity

has led me to the inevitable conclusion, corroborated by experiment, that a reliable and stable microphone of low impedance can be constructed only if the electrode spacing is such, relative to the average grain size, that the effective current paths extend through only two grains, i. e., each current path of minimum resistance involves no more than one carbon-to-carbon contact. This, I have found, can best be achieved only if the electrode spacing lies within the critical range between approximately 2.0 and 2.6 times the average grain diameter. Within this critical range, the conversion ability of the microphone is unusually good. The preferred spacing between the electrodes is apparent from an inspection of Figure 6 and lies within the dimensional range between 2.1 and 2.3 times the average grain diameter.

In this connection, it should be observed that the provision of metallic electrode surfaces having good conductive properties, as by the gold-plating or platinum-plating hereinbefore mentioned, is of outstanding importance in a construction of the present character; since the contacts between the electrodes and the carbon constitute two-thirds of the total number of points of contact resistance, whereas in the conventional microphone having a much smaller ratio between grain size and electrode spacing, these points of contact play only a minor role in the total resistance of each effective current path.

It should also be noted that the term "grains" as used herein is intended to refer generally to comminuted material obtained by crushing or grinding a conductive material such as carbon, whether or not the material ground or crushed is originally of irregular configuration, in sheet form, or in the form of rods or other shapes, and whether or not the resultant "grain" is truly or approximately spherical, or is cube-shaped, of elongated rice-like contour, or otherwise contoured or proportioned. The term "grain diameter" is intended in each case to refer to the dimension as limited by the mesh through which the particles pass; i. e., a grain of 20-mesh diameter (regardless of its shape) is one which will have been held back by a smaller screen but which passes through a screen having square openings arranged twenty to the inch.

In the light of this observation, it will be understood that the spherical shapes shown at 33 in the present drawings are purely illustrative and are not to be construed as restricting the construction or the basic ideas involved to the use of carbon grains having this particular configuration. Moreover, while I have, for the sake of brevity, designated the grains as being "carbon" grains, this term is intended to include within its significance all other materials of equivalent properties suitable to serve the same purpose. Such materials include, for example, pure elements such as silicon and selenium, as well as combinations of metallic and non-metallic substances which are similarly conductive to electric current and have the property of manifesting substantial variations in resistance when the pressure of contact between grains is caused to vary.

In the illustrative construction depicted in Figure 2, the parts are deliberately designed in such a way that the aforementioned critical relationship is maintained. In the first place, I employ grains of substantially uniform size, whose average diameter is between 50-mesh and 10-mesh, the preferred size being 20-mesh. In the second place, the parts are so designed that the

spacing between the electrodes 30 and 31 will be between 2.1 and 2.3 times the average grain diameter. For example, where the grain employed is of 20-mesh size, the spacing between the electrodes is caused to lie between the dimensional values 0.105 and 0.115 inch.

The terms "convex" and "concave" as applied to the electrodes are not intended to restrict the construction to one in which the electrode surfaces are truly spherical in contour, or curved at all. It is within the purview of the invention, for example, that the electrodes might have opposed operative surfaces which are conical or pyramidal in contour, or composed of plane facets arranged at angles to one another. In any case, the one which protrudes may be said to be "convex," in a broad sense, relative to the complementary electrode which is correspondingly "concave."

Where the electrodes are hemispherical, as shown in the present drawings for illustrative purposes, the preferred size of the operative electrode area is achieved when the convex electrode 30 has an outside radius of about 0.1875 inch. Under these circumstances, using a 20-mesh grain, the concave face of the electrode 31 has a radius of approximately 0.2925 to 0.3025 inch. These radii, i. e., of the convex and concave electrode areas, may be increased or decreased, depending upon the use to which the microphone is to be put. On the increasing side, however, a limit is reached when the inertia of the vibratable electrode becomes too great to respond actively to the ordinary human voice. Generally speaking, if the microphone is to be used for a public-address system, which calls for relatively large wattage, the radii may be of the illustrative dimensions given; and where the microphone is to be used for a purpose where a smaller wattage is needed, as in an inter-office communicating system or the like, the radii of the convex and concave electrode areas may be correspondingly reduced. An aid to power consideration is sometimes achieved by using a concentrator or mouth piece on the microphone.

It is contemplated that the microphone will be inserted in a circuit in which there is a low-voltage source of direct current, such as six volts or so. While the source of direct current may be of any suitable character, such as the storage battery of an automobile, it frequently becomes desirable to utilize the present microphone in a circuit in which the source of power is a simple dry cell battery. In such a case, the unitary assembly shown in Figure 5 is of unique advantage. A preferred relationship of the parts is shown in detail in Figures 2 and 3.

Referring to these figures, it will be observed that I have provided the handle 13 in the form of an elongated cylinder, preferably of metal such as aluminum or the like. In its top wall 42 I provide a central aperture in which an insulating bushing 43 is mounted. Projecting through this bushing is a contact element 44 whose inner end is flattened as at 45, whereby it is adapted to establish electric contact with the center pole 46 of a conventional dry cell battery 47 which fits snugly but slidably within the handle 13.

On opposite sides of the contact element 44 I provide two spaced upstanding ears 48 on the end wall 42, through which a pivot pin 49 extends. On the housing of the microphone I provide a similar pair of ears 50 which also fit over the pivot pin 49. This establishes a pivotal connection between the microphone housing and the handle, and by arranging the parts in suitable frictional relationship, the microphone may be

readily adjusted into varying angularities with respect to the longitudinal axis of the handle 13.

Projecting from the microphone is a contact element 51 similar to the element 44. It extends into a bore having a lining 52 of insulating material, this bore extending all the way to the electrode 31. A coil spring 53 is mounted in the inner end of this bore, and serves to establish an electric connection between the electrode 31 and the contact element 51, at the same time serving yieldably to urge the element 51 outwardly.

Mounted on the pivot pin 49, in insulated relation to it, by means of an insulating sleeve or bushing 54, is a bridging contact element 55 having a peripheral contact surface which is concentric with the pivot axis and which establishes contact with both the elements 51 and 44, regardless of the angular position into which the microphone is set.

At the rear end of the housing 13, an end plate 56 of insulating material is fitted, preferably being held in place by friction. It is provided with two spaced apertures 57 into which the usual two prongs 58 of the connector 14 (Figure 5) may be inserted. Within the handle 13, and aligned with the apertures 57, are the connection terminals 59 and 60 adapted to engage with and establish electrical contact with the prongs 58, respectively, when the latter are inserted. The terminal 59 is formed on a ring-shaped disk 61 which is clamped in position by the plate 56, and establishes a permanent electrical connection with the body of the handle 13, hence with the ears 48, 50, the microphone housing, and the vibratable electrode 30. The other connection terminal 60 is mounted on a centrally positioned stem 62 on which a conductive sleeve 63 is mounted, this sleeve having a flattened end 64 pressed by a coil spring 65 into constant electric contact with the rear pole 66 of the battery 67. The stem 62 is preferably threaded on its interior, so that it may be secured to the plate 56 by the screw 68.

The handle 13 may be of any desired length, so that one, two or more dry cell batteries, such as those indicated at 47 and 67, may be accommodated in tandem relationship. Where four batteries of $1\frac{1}{2}$ volts each are used, the total voltage available in the circuit is obviously the 6 volts for which the microphone is primarily intended.

From the description given, it will be obvious that the electrode 30 is in electric contact with the microphone housing, and that there is an insulated electric contact established, by the contact elements 44 and 51, between the insulated electrode 31 and the center pole of the battery. Similarly, it will be observed that one of the connection terminals, i. e., the terminal 60, is in electric contact with the rear pole of the battery, and the other terminal 59 is in electric contact with the microphone housing, whereby the insertion of the plug 14 into the handle 13 completes the electric circuit diagrammatically shown in Figure 1.

In general, it will be understood that many of the details herein described and illustrated may readily be modified by those skilled in the art without necessarily departing from the spirit and scope of the invention as expressed in the appended claims. Except as otherwise specified in the claims, therefore, it is intended that these details be interpreted as illustrative, and not in a limiting sense.

Having thus described my invention and illus-

trated its use, what I claim as new and desire to secure by Letters Patent is:

1. In an electro-mechanical transducer, a pair of spaced electrodes having carbon grains between them, the base of one electrode having a cylindrical contour, and a collar secured to the other electrode and encircling said cylindrical base, said collar and base being separated by an insulating clearance gap which permits free vibration of said first-named electrode in the direction of said cylinder axis and which is small enough, relative to the average grain size, to prevent escape of said grains through it.

2. In an electro-mechanical transducer as defined in claim 1, and one of said electrodes being vibratory and of dome shape, the other of said electrodes being fixed and having a concave recess for receiving said vibratory dome-shaped electrode and uniformly spaced therefrom to receive the carbon grains, said fixed electrode having a plug which is removable to permit access to the space between the electrode for the purpose of filling the same with the carbon particles, the end of said plug being concaved to conform to the surface face of the concaved fixed electrode whereby to maintain the uniformity of the spacing of the electrodes.

3. A carbon-grain microphone comprising a pair of spaced electrodes having carbon grains of predetermined size between them, one of said electrodes being vibratory and having a dome facing the other electrode, said other electrode being fixed and being concaved to receive said vibratory electrode, means for mounting said vi-

bratory electrode, said mounting means enabling said electrode to vibrate in response to sound-wave impulses impressed thereon, the operative electrode area adjoining the grains, the grain size, and spacing means between said electrodes being sufficient to produce an average resistance path through the grains from one electrode to the other being of relatively low order of less than fifteen ohms, whereby the microphone can transmit at low voltage a fluctuating current which is responsive to said impulses and adequate in magnitude, without amplification, to actuate a loud speaker of comparably low resistance.
